(57) **CLAIM**

The ornamental design for a board short pocket flap, as shown and described.

DESCRIPTION

FIG. 1 is a front view in closed orientation illustrating my design for a board short pocket flap;

FIG. 2 is a front view in open orientation thereof;

FIG. 3 is a perspective bottom view in open orientation thereof;

FIG. 4 is a perspective top view in open orientation thereof;

FIG. 5 is a right side view wherein the left side view is a mirror image of the right side view thereof; and,

FIG. 6 is a front perspective view in open orientation thereof.

The broken lines in the drawings illustrate environmental structure and form no part of the claimed design.
